AXEL H. NELSON, OF TURLOCK, CALIFORNIA

CONCRETE STAVE MAKING MACHINE

Application filed December 14, 1927. Serial No. 239,992.

My invention relates to improvements in concrete stave making machines, and it consists in the combinations, constructions, and arrangements hereinafter described and claimed.

An object of my invention is to provide a concrete stave making machine which is adapted to mold concrete into staves which after setting can be used in much the same manner as building blocks in forming the walls of a house, silo, and the like. The particular size of the blocks may differ with the different types of building but I have found that a block approximately 30" long and 15 10 1/2" wide will function the best in forming the walls of a building.

A further object of my invention is to provide a device of the type described which is relatively simple in construction for the number of operations it performs in forming a concrete stave. The forms may be changed for making a stave having a curved surface or having a flat surface.

Heretofore it has been difficult to form staves of the dimensions set forth above, because it was hard to tamp the concrete for forming a solid mass which would set properly. I have overcome this disadvantage by providing a form that can be moved into vertical position so that the tamping can be done from one end of the form and which can then be swung into a horizontal position where the stave may be released from the machine and removed to a place where it is permitted to set.

Other objects and advantages will appear in the following specification, and the novel features of my invention will be particularly pointed out in the appended claims.

My invention is illustrated in the accompanying drawings forming a part of this application, in which

Figure 1 is a side elevation of the machine, portions thereof being shown in section;

Figure 2 is a top plan view of the machine;

Figures 3 and 4 are views of the operating mechanism showing it in two different positions;

Figure 5 is a section along the line 5—5 of Figure 1;

Figure 6 is a section along the line 6—6 of Figure 1;

Figure 7 is an enlarged plan view of a portion of the device; and

Figures 8 and 9 are perspective views of two types of staves formed by the machine.

In carrying out my invention I will first describe the construction of the form, then the mechanism for operating the form, and then the means for conveying the complete stave away from the machine.

The construction of the form is best shown in Figures 1, 5, 6, and 7. It will be noted that this form is composed of a pallet board 1, see Figure 7, that is of a length and width sufficient to support the stave and to cover one of the larger faces thereof. The form board 2 is spaced from the pallet 1 and provides a recess 3 for receiving the concrete. I am assuming that the pallet 1 is in vertical position, which is the position assumed during the initial operation of the machine. The sides of the form consist of dies 4 and 5, these dies being female and male, respectively. The dies extend the entire length of the stave, and are supported by brackets 6, which in turn are carried by small semi-circular discs 7.

Figure 7 further shows how the discs are mounted upon rods 8, which in turn are carried by arms 9. The arms 9 are pivotally secured at 10 to reinforcing bars 11 that extend along the back of the form board 2. The arms 9 have their free ends pivotally connected at 12 to links 13, which in turn extend from the arms 9 to a sleeve 14 slidably mounted upon a shaft 15. It will be noted from the construction thus far that a movement of the sleeve 14 upon the shaft 15 will swing the arms 9 into the dotted line position and will move the dies 4 and 5 away from the form for releasing the complete stave.

In case the adjacent surfaces of the pallet 1 and form board 2 are flat instead of curved, the dies 4 and 5 are swung about the pivots 8 in order to cause these dies to extend at right-angles with respect to the surfaces 16. The means for adjusting the dies comprises setscrews 17, see Figure 7, which are threaded

in the heads 18 of bolts carried by the arms 9. The set screws 17 may be adjusted for permitting the half discs 7 to be swung into the desired positions, whereupon the set screws 5 may be tightened and will hold the discs in place.

Reference to Figure 6 shows how the form board 2 is held in place, the reinforcing bars 11 straddle bolts 19, which in turn are 10 screwed into the board 2. There are two sets of reinforcing bars 11 and these bars are spaced from each other by spacers 20, the spacers being of the shape shown in Figure 7, so as to bear against the form board 2 15 and act as stops for limiting the movement of the board 2 toward the bars 11.

The entire form is mounted upon a shaft 21, the shaft in turn being journaled in bearings and carried by sides 23 of the frame of 20 the machine. The sides 23 are relatively long, as shown in Figure 1, and are supported by legs 24. The shaft 21 is rotatably mounted in the bearings 22 for a purpose hereinafter described. It should be noted that the 25 board 2, pallet 1, and dies 4 and 5 are moved as a unit about the shaft 21.

The means for closing the bottom of the form is shown in Figures 1 and 6, and it will be noted from these figures that a form plate 30 25 is held in place by a clamp 26 that is secured to the board 2 by a bolt 27. In addition to the bolt 27, the plate 25 is secured to the board 2 by bolts 28, see Figure 6. The clamp 26 not only aids in supporting the form plate 25 but extends beneath the pallet 1 35 and supports this with respect to the other parts of the form.

The novel means for locking the pallet temporarily to the form is clearly shown in 40 Figures 5 and 7. It has already been stated that the pallet is supported by the clamp 26. The arms 9 consist of pairs, that is, each side of the form has two arms consisting of a single piece bent back upon itself at the pivot 45 point 12, see Figure 1. The arms are pivotally secured to the bars 11 as stated, and extend beyond the pallet 1 and carry links 29. Figure 1 and Figure 5 show how these links are pivotally mounted at 30 on the ends of the 50 arms 9, so that they may swing in a counter-clockwise direction when looking at Figure 5, and they also pivot about bolts 31. This gives a universal connection between the arms 9 and the links 29. The links 29 are carried by 55 one pair of arms 9 and are removably connected to a pair of hook-shaped members 32, see Figure 7. There are two hook-shaped members one for each link, and they prevent the outward swinging of the links away from 60 the pallet 1. Figure 5 shows how the ends of the links are twisted as at 33 for slidably contacting with the upper surfaces of the arms 9 and for engaging with the hooks 32. The hooks 32 are connected to each other at 65 34 in much the same manner as the pairs of

arms are connected to each other. The hooks are pivoted to the bar 11 by the bolt 10, that also pivotally connects the arms 9 to the bar. I have shown the pallet board as being reinforced by battens 35, and have further 70 shown the pallet board as being provided with U-shaped members 36 for receiving the links 29, see Figure 5. Bolts 37 may be passed through aligned openings in the U-shaped brackets 36 and links 29 for securing 75 these parts together.

When the form is in the vertical position shown in Figure 1 it is filled with concrete by means of a hopper 38, see Figure 1. This hopper is mounted upon a frame 39 with carriage rollers 40, which ride upon rails 41. The hopper is manually moved toward the form until the mouth 42 of the hopper is disposed above the top of the form. The desired amount of concrete is now poured into the form and this is tamped solid while the form still remains in vertical position.

The entire form is now rocked about the shaft 21 as a pivot. This is accomplished by grasping the arms 9 and swinging them from the position shown in Figure 1 into the position shown in Figure 3. Prior to this movement, however, a carrier 43 is moved along the guide-rails 44, see Figure 1, until it is positioned at a point where the pallet 1 will rest upon the carrier when the form is swung into substantially horizontal position, as shown in Figure 3. The cleats or battens 35 of the pallet 1 rest upon cross-members 45 of the carrier 43.

It will be noted from Figures 3 and 4, also 7, that the shaft 21 has a lever 46 rigidly secured thereto. This lever is for the purpose of freeing the dies 4 and 5 and the form board 2 from the cast stave. The first movement of the lever from the position shown in Figure 3 into the position shown in Figure 4 will rock the shaft 21 without rocking the form, since the form is rotatably mounted on the shaft. The rocking of the shaft swings an arm 47, see Figures 3 and 7, that moves the links 48, which in turn slide the sleeve 14 on the shaft or rod 15. As already explained, this movement frees the dies 4 and 5 from the form.

It will also be noted that the shaft 21 carries a cam 48, see Figures 3 and 4, this cam engages with the side members 23 of the frame, after the dies 4 and 5 have been moved clear of the concrete stave. The cam, in 120 swinging from the position shown in Figure 3 into the position shown in Figure 4, will lift the form board 2 together with all of the associate parts with the exception of the pallet 1. It will be seen that the pallet has already been released from the form by the swinging of the arms 9 in the dotted line positions, and the freeing of the links 29 from the hooks 32. The links will drop into the out-of-the-way positions as indicated in Fig- 125 130

ure 4, and are again swung into operative position when the form has been swung into vertical position and a new pallet has been substituted for the one now supporting the complete slab or stave. The concrete is solid enough to keep its shape, even though only supported by the pallets 1. The pallets are removed from the carrier 43 one by one and are stacked in piles so as to give the staves a chance to set and harden. The cleats or battens 35 space the pallets a sufficient distance apart to provide room between adjacent pallets for the staves. If desired a flexible chain 49 may be used for limiting the swinging of the form from the vertical position into the substantially horizontal position. The complete stave is shown in Figures 8 and 9, Figure 8 showing a flat stave 50 having grooves 51 in three of its walls, while Figure 9 shows a curved stave 52 having a groove 53 in one wall and a projection 54 in the opposite wall.

From the foregoing description of the various parts of the device, the operation thereof may be readily understood.

25 The hopper 38 is first filled with concrete, and then this is poured into the form while the form is in vertical position. The concrete is now tamped. The carrier 43 is moved into a position to receive the pallet 1 and the entire form is swung around the shaft 21 so as to position the pallet on the carrier. The lever 46 is now actuated and releases the form from the pallet. The form may now be swung into vertical position again and the pallet removed from the carrier and placed to one side to permit the concrete to set. In Figures 3 and 4 I show guide-strips 55 carried by the cross-piece 45 for swinging the links 29 free of the carrier when the carrier is moved with respect to the form.

40 In Figure 7 I show the form board 2 as having a plate 2' secured to the front thereof by screws 3' or other suitable fastening means. The plate has a convex outer surface and is used when the pallet 1 having a concave inner surface is used. When the operator desires to make a flat stave, the plate 2' is removed and the pallet 1 having a flat surface is substituted for the type of pallet shown in the figure. The changing of the plate 2' obviates the necessity of changing the entire form board 2.

45 One of the principal objects of the invention is to provide a portable machine that can be taken from place to place readily. The machine is transported to the locality where the house, silo, or other building, is to be erected, and the staves are made at this locality. The staves do not have to be transported any distance as is the case with certain types of machines, when the machine oftentimes is in one locality and the building to be erected is in another entirely different locality.

50 Although I have shown and described one

embodiment of my invention, it is to be understood that the same is susceptible of various changes and I reserve the right to employ such changes as may come within the scope of the appended claims.

70

I claim:

1. A concrete stave-making machine comprising a collapsible form, means for holding said form in a vertical position, the top end of said form being open for receiving the self-hardening mixture whereby the mixture may be tamped in the form while being poured thereinto.

2. A concrete stave-making machine comprising a support for contacting with the side of the stave to be formed, removable sides carried by said support, a bottom, a removable pallet board for forming the support for the other side, the three sides, bottom and pallet board constituting a form with an open end, means for swinging the form for positioning the open end at the top, said means being swingable for disposing the pallet board beneath the block, and means for releasing the pallet board from the other three sides and the bottom.

3. A concrete stave-making machine comprising a support for contacting with the side of the stave to be formed, removable sides carried by said support, a bottom, a removable pallet board for forming the support for the other side, the three sides, bottom and pallet board constituting a form with an open end, and means for swinging the form for positioning the open end at the top, said means being swingable for disposing the pallet board beneath the block.

4. A concrete stave-making machine comprising a support for contacting with the side of the stave to be formed, removable sides carried by said support, a bottom, a removable pallet board for forming the support for the other side, the three sides, bottom and pallet board constituting a form with an open end, and means for swinging the form for positioning the open end at the top.

5. A concrete stave-making machine comprising a collapsible form having removable sides and an open top, means for swinging the form for positioning the open end at the top, one of said sides constituting a pallet board, said means being swingable for disposing said pallet board beneath the block.

AXEL H. NELSON.
